(57) **CLAIM**

The ornamental design for a modular pallet, substantially as shown and described.

DESCRIPTION

FIG. 1 is a front perspective view of a modular pallet showing my new design;

FIG. 2 is a bottom perspective view thereof;

FIG. 3 is a top view thereof;

FIG. 4 is a bottom view thereof;

FIG. 5 is a front end view thereof, and the opposite end view is identical; and,

FIG. 6 is a right side view thereof, and the opposite side view is identical.

The broken lines in the figures are to show portions of the modular pallet and form no part of the claimed design.
